NUTCRACKER.

1,194,837.

Specification of Letters Patent. Patented Aug. 15, 1916.

Application filed April 3, 1916. Serial No. 88,678.

To all whom it may concern:

Be it known that I, FREDERICK HACHMANN, a citizen of the United States, and residing at St. Louis, in the State of Missouri, have invented a certain new and useful Improvement in Nutcrackers, of which the following is a specification.

This invention relates to nut cracking devices of the type adapted for attachment to a table or other support and to be manually operated. These devices embody in their organization a pair of coöoperating jaws arranged to receive the nut endwise between them and to be moved relatively toward each other with sufficient force to break or crack the nut hull. The operation of the devices involves an initial relative adjustment of the jaws to approximately the size of the nut, positioning the nut between the jaws and finally moving one of the jaws forcibly to crack the nut. It has been proposed heretofore to make both jaws movable in order that the one might be shifted to effect the desired initial adjustment and the other operated, usually by means of a power lever, for supplying the requisite force to crack the nut. When the devices are so constructed it becomes necessary to employ one hand for manipulating the power jaw and the other for performing the two remaining operations of shifting the adjustable jaw and placing the nut to be cracked. In consequence of these two operations being the work of the one hand not only is an appreciable loss of time incurred, but the initial adjustment or setting of the device must take place prior to introducing the nut between the jaws and, therefore, accurate adjustment becomes practically impossible. As an improvement on such devices it has been proposed to equip such a device with a single movable jaw adapted for manipulation in effecting both the initial rapid adjustment and the application of the final nut cracking force, but these later structures, as heretofore devised, present objectionable features in matters of both construction and operation and, therefore, such devices, of themselves, become the subject of improvement under the present invention.

This invention has among its objects, therefore, to overcome the above noted objections by providing a device whereby the nut cracking operation may be carried for-

ward without loss of time and one wherein an accurate adjustment to accord with variations in the sizes of the nuts may be readily effected.

Further objects are to simplify the construction and operation, and reduce the cost of production, of such devices.

With the above and other objects in view, the invention comprises the novel features of construction and combination of parts more fully hereinafter described.

In the accompanying drawings, Figure 1 is a side elevation of a device embodying the invention, showing the same mounted ready for use, the support being shown in section; Fig. 2 is a detail view partly in section taken on the line 2—2 of Fig. 1; Fig. 3 is a view similar to Fig. 1, showing a slightly modified construction; Fig. 4 is a detail view partly in section taken on the line 4—4 of Fig. 3, and Fig. 5 is a detail view, partly in section, taken on the line 5—5 of Fig. 1.

In accordance with the embodiment of the invention herein shown, it becomes necessary to make only one of the jaws movable, as provision is made for manipulation of the one jaw in effecting both the initial rapid adjustment to accord with the size of the nut and the final application of force for cracking the latter, it being noted that thus, one hand remains free at all times for handling the nuts and that, in consequence the nut to be operated upon may be introduced into place between the jaws prior to effecting the desired initial adjustment, whereby such adjustment may be accurately performed and the other steps of the nut cracking operation be carried forward rapidly and without loss of time.

Referring to the drawings, it will be seen that the device, which is adapted to be mounted for use upon a support 1, comprises an elongated body 2, provided near its forward end with a depending portion or bracket 3 having a rearwardly projecting arm 4 extending substantially parallel with the body 2 and terminating in a boss 5, through which is tapped a clamping screw 6 operable for clamping the device on the support 1.

Formed, or otherwise provided, on the forward end of the body 2, is a fixed jaw 7 disposed for coöperation with a movable jaw 8 mounted, preferably by a ball and

socket connection 9, upon the forward end of an actuating member or shaft 10 adapted for manual operation and having its rear end equipped for this purpose with a hand piece 11.

5 The forward portion of the member or shaft 10 is made in the form of a power screw 12 arranged to work through an adjustable ratchet block 13 slidably disposed upon the rear portion of the body 2, the said block, which is channeled at 14 to seat over said body, being provided with a tooth 15 formed for coercive engagement with any one of a series of teeth 16 provided on the body 2, it being noted that the block has sufficient movement or play relative to the body to permit of disengagement of the tooth 15 from the teeth 16, in effecting adjustments of the block, and that the ball and 20 socket connection 9 provides for such manipulation of the block through the medium of the shaft 10.

In practice the device having been mounted and clamped upon the support 1, as shown, the operator grasps the grip piece 11 of the shaft 10, with one hand and with the other holds the nut to be placed between the jaws. The shaft 10 is then tilted slightly upward, to the dotted line position in Fig. 1, thereby freeing block 13 from engagement with rack 16 whereupon the shaft may be shifted bodily for moving jaw 8 rearward to permit introduction of the nut into position between the jaws. An initial relative 35 adjustment of the jaws to accord with the size of the nut is now effected by shifting the shaft 10 bodily forward, thereby moving the jaw 8, mounted on said shaft, to position against the nut. The shaft is now swung 40 downward causing tooth 15 to engage one of the teeth 16 and fix the block 13 against movement whereupon rotation of the shaft operates through action of its threaded portion 12 in the block to move the jaw 8 with 45 sufficient force to crack the nut between the jaws.

In order that the movable jaw 8 may, during the above operation of the device, correctly follow its proper path of movement 50 toward and from the fixed jaw 7, the said jaw 8 is, as shown in Figs. 1 and 2, provided with a guide portion or box 17, formed to slidably engage the side edges 18 of the body 2, for guiding the jaw in its movements, 55 while in the embodiment shown in Figs. 3 and 4, the side edges of the body are, throughout a portion of their length, extended upwardly forming guides 19 disposed and arranged to guide the jaw 8, as will be 60 readily understood.

In that embodiment of the invention shown in Fig. 1, the jaw 8 is, as seen more clearly in Fig. 5, provided with a vertical slot or channel 20 having the ball receiving 65 socket at its upper end and affording pas-

sageway for the shaft 10. Provision is thus made for effecting ready assemblage of the parts in making the ball and socket connection 9.

It is to be particularly observed that in 70 the operation, above described, the relative movements of the jaws both for attaining the initial adjustment and also the application of force to break the nut hull are accomplished by manipulation of the one movable 75 jaw 8, through the medium of the screw shaft 10 and that a comparatively slight rotation of the latter will, after the initial adjustment, be effective for cracking the nut. Furthermore, it will be seen that in the operation 80 of this device one hand remains free at all times for use in introducing the nuts into, or removing them from, position between the jaws and that consequently the work may be performed smoothly and 85 rapidly.

From the foregoing it will be seen that the device fully accomplishes its stated objects, in the attainment of which, the invention is not necessarily restricted to the structural 90 details herein disclosed, as various minor changes may be made therein without departing from the spirit or scope of the invention.

Having thus described the invention, what 95 is claimed is:

1. A nut cracking device comprising a body portion, a bearing block adjustably mounted thereon, a pair of nut cracking jaws, one of said jaws being movable with said block 100 for effecting an initial rapid adjustment of the jaws, relatively, to accord with the size of the nut and independently of the block for exerting a nut cracking force, means for holding the block in adjusted positions, and 105 means associated with said block for effecting said independent movement of said jaw, constructed and arranged to release the block from engagement with said body.

2. A nut cracking device comprising a 110 body portion having a jaw, a bearing block mounted on said body for adjustment toward and from said jaw, means for holding the block in adjusted positions, a movable jaw interposed between said first named jaw 115 and block and movable with the latter for effecting an initial rapid adjustment of the jaws, relatively, to accord with the size of the nut, and an operating member connecting said movable jaw on said block and operable for effecting an independent movement of the jaw to exert a nut cracking force, said member being constructed and arranged for movement to release the block from said body. 120

3. A nut cracking device comprising a body having a jaw, a bearing block mounted on said body for adjustment toward and from said jaw, means for holding said block in adjusted positions, a movable jaw inter- 130

posed between said block and first named jaw and adapted for coöperation with the latter in cracking the nuts, and an actuating screw operatively engaged with said block and movable jaw and connecting the latter for movement with the block in effecting an initial rapid adjustment of the jaws to ac-

cord with the size of the nut, said screw being operable for effecting independent movement of said movable jaw to crack the nut and for releasing said block from said body.

In testimony whereof I affix my signature this 28 day of February, 1916.

FREDERICK HACHMANN.
